PEDESTAL DRINKING FOUNTAIN

Terry R. Haws, Lafayette, Calif., assignor to Haws
Drinking Faucet Co., Berkeley, Calif.

Filed Aug. 5, 1974, Ser. No. 494,397

Term of patent 14 years

Int. Cl. D23—01

U.S. Cl. D23—13

FIG. 1.

FIG. 3.

FIG. 2.

FIG. 4.

FIG. 5.

FIG. 6.

FIG. 7.

FIG. 1 is a perspective view of a pedestal drinking fountain showing my new design;

FIG. 2 is a side elevation thereof;

FIG. 3 is a top plan view thereof;

FIG. 4 is an end elevation thereof;

FIG. 5 is an elevation taken from the side opposite that shown in FIG. 2;

FIG. 6 is an elevation taken from the end opposite that shown in FIG. 4; and

FIG. 7 is a bottom plan view thereof.

The broken line representation of a drinking fixture in FIGS. 1 through 6 is for purposes of illustration only. I claim:

The ornamental design for a pedestal drinking fountain, substantially as shown and described.
